CHAIR IRON

Filed Sept. 20, 1930

UNITED STATES PATENT OFFICE

HENRY W. SHELDICK, OF GARDNER, MASSACHUSETTS, ASSIGNOR TO COLLIER-KEY-WORTH COMPANY, OF GARDNER, MASSACHUSETTS, A CORPORATION OF MASSACHUSETTS

CHAIR IRON

Application filed September 20, 1930. Serial No. 483,240.

Tilting office chairs are commonly provided with springs which tend to maintain the chair seat substantially horizontal, but as heretofore constructed when such a chair is tilted, its motion is stopped suddenly at its limit of tilt, which produces an unpleasant shock to the occupant of the chair. One of the objects of this invention is to provide a construction of chair iron in which the last portion of tilting movement is met with increased resilient resistance so that the shock of sudden stopping is eliminated or much reduced.

Further features of this invention relate to structural improvements of the iron, more particularly for preventing accidental detachment of the J-washer and to the control and limitation of relative movement of certain of the parts.

For a more complete understanding of this invention, reference may be had to the accompanying drawing in which

Figure 1 is a top plan of the chair iron.

Figure 2 is a side elevation thereof showing parts of the chair seat and base to which the iron is applied.

Figure 3 is a vertical section through the spindle portion of the iron.

Figure 4 is a section on line 4-4 of Figure 3.

Figures 5 and 6 are detail sections on lines 5-5 and 6-6, respectively, of Figure 2.

Figure 7 is a section substantially on line 7-7 of Figure 1, but showing the parts in chair-tilted position.

Figure 8 is a similar view but with the chair horizontal and showing a modification.

Referring to the drawing, at 1 are shown side rail or "spider" elements which may, if desired, be of angle section and which support the chair seat shown at 2 in Figure 2. These elements 1 are shown as secured at substantially their central portions to a U-shaped member 5 having side walls 6 (see Figure 6) and a closed end wall 7. This U-shaped member is pivoted on a rod 8 to side wall portions 9 of a U-shaped support which is shown as having a bottom wall 10 upwardly domed at its central portion as at 11 and through which extends the upper

portion of the chair spindle 12, the upper end of which is shown as riveted over against a bridge plate 13 having upwardly turned end flanges 14 secured to and between the walls 9. The pivot 8 for the chair-supporting member passes through the walls 6 and 9 and the flanges 14, and the elements 1. By this construction the chair seat-supporting member comprising the elements 1 and the parts carried therewith are supported for tilting movement from the horizontal seat-supporting position shown in Figures 2 and 8. The extent of this motion may be limited by stop portions 20 struck inwardly from the wall members 6 between stop portions 21 struck outwardly from the material of the walls 9. The chair seat is normally held in horizontal position by resilient holding means. To this end a screw rod 25 is shown as extended through an opening through the wall member 7 and having its head bearing at its inner end against a U-shaped yoke member 27 which may have a channel cross section in its intermediate portion and which is pivotally secured to the inner faces of the walls 9 as at 24 below the seat proper. The member 27 is thus pivoted out of line with but parallel to the seat pivot rod 8. With this arrangement a small initial movement of the seat from its central position produces considerable motion of the spring so that the centering action of the spring is increased. The outer threaded end of this rod 25 has thereon a nut 28 having an actuating hand wheel 29 at its outer end, this nut pressing against a spring seat member 30 which houses the outer ends of coil springs 31, the inner ends of which engage the outer face of the plate portion 7 surrounding centering lugs 32.

In order that there may be no severe shock when the seat reaches fully tilted position as shown in Figure 7, auxiliary spring means for cushioning the last portion of the tilting movement are provided. As shown in this Figure and also in Figure 8 this means may comprise leaf springs 35, each fixed at one end as by the rivets 36 to the top flange 37 of one of the elements 1 and provided at its

free end with a tongue portion 38 projecting through an opening 39 in the flange 37 and positioned to strike upon the upper edge portion 40 of the flange 14 or of the upper edge of the side wall 9 as the seat support having been substantially tilted approaches its fully tilted position, thus to deflect the spring 35, as shown in Figure 7, and add an additional yielding resistance to the tilting of the seat. In place of this auxiliary spring 35 or in addition thereto, if desired, springs formed to present increased rate of resistance to the tilting of the chair as it approaches its limit of tilting position may be employed in place of the coil springs 31 shown in Figures 1, 2 and 7. For example, such springs may comprise conical volute springs such as shown at 45 in Figure 8. These springs have portions of different diameters, the portions of small diameters producing a greater resistance to the tilting movement than the coils of larger diameter. Thus as such springs are compressed the larger coil portions bring up against each other in the initial stages of movement, whereupon the smaller coil portions are successively brought into action and exert an increasingly heavy resistance to further tilting movement. In Figure 8 the spring 35 as well as the spring 45 of the conical volute type are employed.

The spindle 12 hereinbefore referred to is externally threaded at its upper portion only, as shown best in Figure 3, and on this threaded portion is engaged a nut 50 provided with the usual bell member 51 secured at its upper end thereto and housing a J-washer indicated generally at 52 and the upper end of a sleeve 53 which may be supported in the base member 54 of the chair which is provided with the supporting leg 55. While the J-washer may be of any desired type, it is shown as a combined J-washer and ballbearing as shown and claimed in the application for patent of Collier and Sheldrick Serial Number 451,938, filed May 13, 1930. As is customary with J-washers it is provided with a suitable spline 54 (see Figure 4) slidable in a key slot 55 extending lengthwise of the spindle 12 and to its lower end.

The upper portion of the sleeve 53 is shown as provided with a peripheral groove 56 within which may be removably engaged the inner end of a screw 57 which is passed through an opening 58 in the lower flange 59 of the bell member 51 and is threaded through a cross member or bar 60 having its ends secured as at 61 to the flange 59 of the bell member. This permits relative rotation between the spindle and sleeve and also ready disassembly thereof as for ease in packing and shipping. This bar 60 may be of such shape that after being secured permanently and rigidly secured to the bell member and after the 65 J-washer has been placed in position, as in

Figure 4, it will project beneath the outer edge of the J-washer 52 thus to prevent the removal of the J-washer from the lower end of the spindle when the spindle has been taken from the sleeve 53 after retraction of the screw 57 sufficiently for this to be accomplished. This bar 60 may be straight when initially secured in place, and then may or may not be bowed or deformed inwardly after the assembly of the J-washer on the spindle; or one end may be left loose until after such assembly and then secured in place to prevent subsequent removal of the J-washer.

From the foregoing description of certain embodiments of this invention, it should be evident to those skilled in the art that various changes and modifications may be made without departing from the spirit or scope of this invention as defined by the appended claims.

I claim:

1. In combination, a supporting member, a seat-carrying member pivoted to said supporting member for tilting movement away from horizontal seat position, a leaf spring fixed at one end to one of said members, and an element carried by the other of said members in position to deflect the free end of said spring only when said seat-carrying member is tilted to a substantial extent.

2. In combination, a support, a seat-carrying member pivoted to said support for tilting movement away from horizontal seat position to a limited extent, resilient means for opposing such tilting throughout its range, and other means for yieldingly opposing such tilting movement adjacent to its limit only.

3. In combination, a support, a member pivoted to said support for tilting movement, a pair of spaced seat-supporting rails fixed to said member, and a leaf spring fixed at one end to the upper face of each rail and having a finger portion at its free end projecting through a hole in said rail in position to impinge on said support when said member has been tilted to a predetermined position to flex said springs on further tilting of said member.

4. In combination, a spindle externally threaded at its upper portion only and having a key slot extending to its lower end, a nut engaging the threaded portion of said spindle, a sleeve surrounding said spindle and having a peripheral groove at its upper end, a J-washer between said nut and sleeve and having a spline engaging in said groove, removable means carried by said nut engageable in said peripheral groove for retaining said sleeve on said spindle, and a cross member carried by said nut located beneath said J-washer for preventing the removal of said J-washer from the lower end of said spindle on removal of said sleeve.

5. In combination, a spindle externally threaded at its upper portion only and hav-

ing a key slot extending to its lower end, a nut engaging the threaded portion of said spindle, a bell member fixed to said nut, a J-washer on said stem beneath said nut and 5 within said bell member and having a spline engaging in said groove, and a bar having both ends fixed to the inner face of said bell member and a middle portion located in a position beneath said J-washer to prevent said 10 J-washer from being removed at the lower end of said spindle.

6. In combination, a support having spaced side walls, a seat-carrying member having spaced side walls pivoted to said support 15 walls and a connecting portion joining said member side walls, a U-shaped yoke member pivoted at its sides to the sides of said support, a rod fixed to said yoke member and extending through an opening through said 20 connecting portion, a spring seat on the outer end of said rod, and spring means positioned between said spring seat and connecting portion.

In testimony whereof I have affixed my 25 signature.

HENRY W. SHELDRICK.
